UNITED STATES PATENT OFFICE.

ISAAC H. MILLIKEN, OF ASPINWALL, AND WILLIAM J. REGAN, OF PITTSBURGH, PENNSYLVANIA, ASSIGNORS TO THE MC CONWAY & TORLEY COMPANY, OF PITTSBURGH, PENNSYLVANIA, A CORPORATION OF PENNSYLVANIA.

UNCOUPLING MECHANISM.

1,417,545.

Specification of Letters Patent. Patented May 30, 1922.

Application filed October 6, 1921. Serial No. 505,692.

To all whom it may concern:

Be it known that we, ISAAC H. MILLIKEN and WILLIAM J. REGAN, citizens of the United States, residing, respectively, at Aspinwall, 5 in the county of Allegheny and State of Pennsylvania, and Pittsburgh, in the county of Allegheny and State of Pennsylvania, have invented certain new and useful Improvements in Uncoupling Mechanism; and 10 we do hereby declare the following to be a full, clear, and exact description of the invention, such as will enable others skilled in the art to which it appertains to make and use the same.

15 Our invention relates to uncoupling mechanism for actuating the lock of a car coupler to permit the coupler knuckle to move to open position. The particular embodiment of the invention illustrated in the drawings 20 is especially well adapted for application to the Master Car Builders' standard D-type coupler employing a bottom operated lock, but it is apparent that an uncoupling mechanism constructed in accordance with the 25 invention may be applied to other forms of couplers.

The primary object of the invention is to provide a reliable uncoupling mechanism of simple and compact form enabling the train 30 man easily to effect an unlocking operation of the coupler lock.

Generally stated, the principal feature of the invention consists in actuating the lock of a car coupler by means of a rotatable member whose center of rotation is located to 35 the rear of the lock at a fixed distance from the adjacent end of the car, the said member being supported rearwardly of said lock by swinging means adapted to turn upon the 40 center of rotation of the rotatable member.

A further feature of the invention consists in employing a rotatable member to effect an 45 unlocking movement of the coupler lock, and in supporting said rotatable member by means adapted to swing lengthwise of the car and capable of applying to said member a force couple effecting an unlocking rotation of the latter.

Another feature of the invention consists 50 in actuating the lock of the car coupler by means of a rotatable member which is supported rearwardly of said lock by a device adapted to swing lengthwise of the car and

with respect to which the rotatable member is slidably movable.

There are other features of the invention residing in details of construction and in combinations of parts, as will hereinafter appear and be pointed out in the claims.

In the drawings illustrating the invention, 60 the scope whereof is pointed out in the claims,—

Figure 1 is a view, partly in side elevation and partly in section, of an uncoupling mechanism embodying the invention, the car 65 coupler shown being of the well known Master Car Builders' standard D-type.

Figure 2 is a view, partly in side elevation and partly in vertical section, of a portion of the construction illustrated in Fig. 1, the 70 parts being shown in the positions they occupy when the coupler lock has been caused to perform an extended unlocking movement.

Figure 3 is a detail sectional view on the 75 line 3—3, Fig. 1.

Figure 4 is a detail view, partly in side elevation and partly in vertical section, of the rear portion of the mechanism.

Figure 5 is a detail sectional view on the 80 line 5—5, Fig. 1, portions of the uncoupling levers and a portion of the swinging support being broken away.

Figure 6 is a detail plan view of the rear portion of the uncoupling mechanism, parts 85 of the uncoupling levers and a portion of the forwardly extending rotatable member being broken away.

Figure 7 is a detail end elevation of the 90 rear end of the mechanism, portions of the uncoupling levers being broken away.

The car coupler 1 illustrated in the drawings is of the Master Car Builders' standard D-type having a lock 2 which is movably connected to a link 3 that projects downwardly through the coupler head. The link 95 3 is pivotally connected to a swinging lift lever 4 which latter is itself pivotally attached to the under side of the coupler head. The link 3 and pivoted lift lever 4 may be 100 and preferably are constructed and arranged in conformity to the standard practice of the bottom lock lift devices of the D-coupler.

If it is desired to provide for a wide range 105 of lateral movement of the car coupler its

shank may be formed with a pivot pin opening 5 which is adapted to receive a tail pin (not shown) for pivotally connecting the coupler to the draft rigging in a well known manner.

Operatively connected to the swinging member 4 is a vertically rotatable member 6 which is movably supported rearwardly of the coupler lock by a link device 7. This link device 7 is adapted to swing both lengthwise and transversely of the car so as to accommodate itself to the unlocking rotation of the member 6 in any position which the coupler may assume in service. The swinging device 7 may be conveniently suspended directly from the coupler carrier iron 8 through the intervention of a hook and eye connection, the swinging member being provided at its upper end with a hook 9 which projects through a transversely elongated eye 10 formed in the carrier iron.

The forward end of the vertically rotatable member 6, which is preferably a simple bar, is fashioned with a hook 11 adapted to cooperate with the eye or aperture 12 at the inner end of the pivoted member 4, the members 4 and 6 thus being operatively connected in an interlocked manner. The rear end of the rotatable member 6 projects through an opening 13 in the swinging support 7 and is slidably movable with respect to said support, the latter preferably being provided with a convex face or seat 14 located in the vertical axis of the swinging support 7 and adapted to engage the under side of the rotatable member 6.

The swinging support 7 is provided with a plurality of vertically spaced lugs 15 and 16, respectively, between which the rotatable member 6 extends. As will be seen upon reference to Fig. 2, these lugs are adapted to engage opposite sides of said rotatable member to apply thereto a pair of forces constituting a force couple inducing its unlocking rotation. To increase the area of contact of the lugs 15 and 16 with the member 6, the inner faces of said lugs may, as shown, be of beveled form. Preferably the opening 13 in the swinging support 7 is of sufficient size and the side walls 17 of said support are spaced sufficiently far apart to permit the rotatable member 6 to have some angling movement transversely of the car with respect to the swinging support. By this means the swinging support 7 is not required to move to the extent that would be necessary if it alone were compelled fully to compensate for the various angular positions which the rotatable member 6 may assume as the result of lateral swinging movements of the coupler.

To effect an unlocking movement of the member 6 the swinging device 7 is preferably adapted to be actuated by a plurality of uncoupling levers 18. These levers ex-

tend toward the sides of the car and preferably are of the well known form illustrated in the I. H. Milliken Patent No. 1,184,116 dated May 23, 1916. The levers, either of which may be operated to rotate the swinging device 7 upon its supporting eye 10 as a center, are provided with upturned ends 19 which are respectively adapted to enter openings 20 at opposite sides of the swinging support. When either of the uncoupling levers 18 is rotated in the proper direction its upturned end presses against the swinging support 7 and compels it to perform a corresponding rotation, thereby causing the lugs 15 and 16 to grip the rotatable member 6 and force it to execute an unlocking movement.

In assembling the mechanism the hook 11 of the vertically rotatable member 6 is hooked through the eye 12 of the pivoted member 4 and the swinging support 7 is then placed upon the rear end of the member 6. The swinging support is thereafter turned laterally until it is at right angles to its normal position when its hook 9 may be inserted in the eye 10 of the carrier iron. The supporting member is then dropped to ordinary position and the upturned ends 19 of the uncoupling levers are inserted through the openings 20 in the sides of the swinging support. The outer ends of the uncoupling levers 18 are then engaged with supporting brackets near the sides of the car in the usual manner. When so assembled the parts are interlocked against accidental disassociation.

In draft and buffing movements of the coupler 1 the rotatable member 6 slides through the swinging support 7 as may be necessary. During an unlocking operation the supporting device 7 swings lengthwise of the car as may be required to cause the rotatable member 6 to effect an unlocking movement of the pivoted member 4 carried by the coupler head.

We claim:

1. In an uncoupling mechanism, the combination with a car coupler and its lock, of means for moving said lock to unlocked position, said means involving a rotatable member operatively connected to said lock and extending rearwardly therefrom, the center of rotation of said member being to the rear of said lock and at a fixed distance from the adjacent end of the car, and swinging means for supporting said rotatable member, said last named means being movable with respect to said rotatable member and being adapted to swing upon the center of rotation of said member.

2. In an uncoupling mechanism, the combination with a car coupler and its lock, of means for moving said lock to unlocked position, said means involving a rotatable member operatively connected to said lock

and extending rearwardly therefrom, and swinging means movable with respect to and supporting said rotatable member, said swinging means being adapted to swing 5 lengthwise of the car about the center of rotation of said member.

3. In an uncoupling mechanism, the combination with a car coupler and its lock, of means for moving said lock to unlocked position, said means involving a vertically rotatable member operatively connected to said lock, a swinging support for said rotatable member located rearwardly of said lock and adapted to swing lengthwise of the car, and 10 an uncoupling lever supported at one end by and adapted to actuate said swinging support to cause a vertical rotation of said rotatable member, said rotatable member being adapted to slide with respect to said 15 support and to be engaged on opposite sides by the latter.

4. In an uncoupling mechanism, the combination with a car coupler and its lock, of means for moving said lock to unlocked position, said means involving a vertically rotatable member operatively connected to said lock, a rotatable uncoupling lever, and means adapted to swing lengthwise of the car affording a support for said vertically 20 rotatable member and said uncoupling lever, said vertically rotatable member being adapted to be engaged on opposite sides by said supporting means, and said uncoupling 25 lever being adapted to actuate said supporting means.

5. In an uncoupling mechanism, the combination with a car coupler and its lock, of means for moving said lock to unlocked position, said means involving a rotatable member operatively connected to said lock, means adapted to swing lengthwise of the car affording a support for said rotatable member, and an uncoupling lever adapted to actuate 30 said supporting means, said supporting means when actuated by said uncoupling lever being adapted to transmit to said rotatable member a force couple effecting an 35 unlocking rotation of said rotatable member.

6. In an uncoupling mechanism, the combination with a car coupler, its lock and carrier iron, of means for moving said lock to unlocked position, said means involving a rotatable member operatively connected to said lock, means movably connected to said 40 carrier iron and adapted to swing lengthwise of the car affording a support for said rotatable member, and an uncoupling lever adapted to actuate said supporting means, said supporting means when actuated by 45 said uncoupling lever being adapted to transmit to said rotatable member a force couple effecting an unlocking rotation of said rotatable member.

7. In an uncoupling mechanism, the combination with a car coupler, its lock and car-

rier iron, of means for moving said lock to unlocked position, said means involving a rotatable member operatively connected to said lock, means movably connected to said carrier iron affording a support for said 50 rotatable member, and means for actuating said supporting means to cause the latter to effect an unlocking rotation of said rotatable member, said supporting means being adapted to swing both lengthwise of the car 55 and transversely thereof.

8. In an uncoupling mechanism, the combination with a car coupler, its lock and carrier iron, of means for moving said lock to unlocked position, said means involving a 60 rotatable member, swinging means carried by said coupler for movably connecting said rotatable member to said lock, means for supporting said rotatable member rearwardly of said lock, and means for actuating 65 said supporting means to effect an unlocking rotation of said rotatable member, said supporting means and said carrier iron having a hook and eye connection, said rotatable member being slidable with respect to said 70 supporting means, and said rotatable member being adapted to be operatively engaged on opposite sides by said supporting means.

9. In an uncoupling mechanism, the combination with a car coupler and its lock, of 75 means for moving said lock to unlocked position, said means involving a rotatable member, means adapted to swing lengthwise of the car affording support for said rotatable member rearwardly of said lock, and an uncoupling 80 lever extending transversely of the car and adapted to actuate said swinging means to effect an unlocking rotation of said rotatable member, said swinging means being provided with an opening through 85 which said rotatable member is slidably movable and also being provided with vertically spaced lugs which are respectively adapted to engage opposite sides of said 90 rotatable member.

10. In an uncoupling mechanism, the combination with a car coupler and its lock, of means for moving said lock to unlocked position, said means involving a rotatable member operatively connected to said lock, a 95 swinging device affording a support for said rotatable member rearwardly of said lock and adapted to effect an unlocking rotation of said member, and an uncoupling lever adapted to actuate said swinging device, said 100 swinging device having an opening adapted to receive the rear end of said rotatable member and having an opening adapted to 105 permit the entry of said uncoupling lever.

11. In an uncoupling mechanism, the combination with a car coupler, its lock and carrier iron, of means for moving said lock to unlocked position, said means involving a 110 rotatable member, swinging means for movably connecting said rotatable member to 115

said lock, a swinging device affording a support for said rotatable member rearwardly of said lock and adapted to effect an unlocking rotation of said member, and an uncoupling lever movably engaging said swinging device and extending therefrom toward the side of the car, said swinging device being provided with a plurality of vertically spaced lugs adapted to engage said rotatable member and between which said member extends and also being provided with means of attachment to said carrier iron.

12. In an uncoupling mechanism, the combination with a car coupler, its lock and carrier iron, of means for moving said lock to unlocked position, said means involving a rotatable member, swinging means for movably connecting said rotatable member to

said lock, a swinging device affording a support for said rotatable member rearwardly of said lock and adapted to effect an unlocking rotation of said member, and means for actuating said rotatable member through the intermediacy of said swinging device, said swinging device having a plurality of vertically spaced lugs between which said rotatable member extends and also having a convex seat upon which said rotatable member is slidably supported, said swinging device and said carrier iron having a hook and eye connection.

In testimony whereof we affix our signatures.

ISAAC H. MILLIKEN.
WILLIAM J. REGAN.
